UNITED STATES PATENT OFFICE.

ALBERT M. WARD, OF ROCHESTER, NEW YORK.

CHECK-WRITING MACHINE.

1,386,479.

Specification of Letters Patent.

Patented Aug. 2, 1921.

Application filed August 14, 1920. Serial No. 403,588.

To all whom it may concern:

Be it known that I, ALBERT M. WARD, a citizen of the United States, residing at Rochester, in the county of Monroe and 5 State of New York, have invented certain new and useful Improvements in Check-Writing Machines, of which the following is a specification.

The object of this invention is to provide 10 a new and improved form of check writing machine.

Another object of this invention is to shred or perforate the portion of the paper on which the printing is done in a new and 15 improved manner.

These and other objects of this invention will be fully illustrated in the drawings, described in the specification and pointed out in the claims at the end thereof.

20 In the accompanying drawings:

Figure 1 is a side elevation of the check writing machine showing the right hand side thereof.

Fig. 2 is an elevation of the left hand 25 side of the machine, showing a part of the casing of the machine broken away.

Fig. 3 is a vertical section of the machine, the section being taken on the line 3^x—3^x of Fig. 4.

30 Fig. 3^A is a vertical sectional view of the type wheel.

Fig. 4 is a front elevation of the machine with a portion of the casing thereof broken away.

35 Fig. 5 is a detail sectional view of the shredding or perforating mechanism, the section being taken on the line 5^x—5^x of Fig. 6.

Fig. 6 is a detail sectional view of the 40 shredding or perforating mechanism, the section being taken on the line 6^x—6^x of Fig. 5.

Fig. 7 is a detail view of the inking roller.

45 Fig. 8 is a detail perspective view of the shredding wheel with a portion of a check shredded thereby.

Fig. 9 is a vertical section of the shredded portion of a check.

50 Fig. 10 is a detail top plan view of the index guide for properly locating the check with relation to the printing and shredding means in the machine.

Fig. 11 is a vertical sectional view of the machine, showing a modified form of spacing mechanism.

Fig. 12 is an end elevation of the type wheel and spacing arm used in the machine illustrated in Fig. 11.

Fig. 13 is a detail view of a modified form of release for the paper feed and shredding 60 mechanism.

Fig. 14 is a detail perspective view of the parts comprising the driving mechanism for the spacing, feeding and shredding mechanism.

In the several figures of the drawings, like reference numerals indicate like parts.

My improved check writer is contained in a housing 1 made preferably of cast iron, which housing comprises a base 2 and a hood 3. The base extends forward of the hood and the forwardly extending portion is open at both the top and the bottom and is separated from the hood at the front by a slot 4 which serves to receive the check for the 70 printing or writing operation. The opening on the top of the base is covered by a plate 5, on which the check rests when it is passed through the machine. The plate 5 is curved downwardly at the rear thereof as shown at 80 5^A. This downwardly curved portion of the plate 5 is adapted to project below the shoulders 100 and 101 by which it is held in place in the housing at the rear thereof. The front of the plate is fastened to the 75 housing by two screws which pass through the top of the plate near each of the outer corners thereof, as indicated at 103 in Fig. 3.

In the right and left hand side walls of the upper portion of the housing are provided suitable bearings in which the shaft 6 is mounted to rotate. This shaft carries the type wheel 7, which is suitably fastened thereto on the inside of the casing. On the outer end of the shaft 6 is fastened a knurled 90 handle 8 by means of which the shaft and the type wheel are adapted to be turned. The shaft 6 is provided on the end near the knurled wheel 8 with the annular recess 9, which recess is engaged by the head of the screw 10, which screw is threaded into the housing.

By turning this screw in or out, the shaft 6 is adjusted longitudinally and is at all times held in position thereby. This screw acts as an adjustable stop for the spacing arm 12 on its reverse movement and stops it in position to just clear the type wheel. It positions the type wheel 7 independently of the housing 1 but with relation to the spacing arm 12.

110

The type wheel is provided with a series of lines of type 11 thereon, each line of which is capable of printing a word, which words are of variable length. On the inside 5 of the type wheel are cast a series of grooves, one for each line of type, which grooves are of variable length, the length of each groove being supplemental to the length of the line of type with which it coöperates. It will 10 also be understood that the groove is not necessarily placed near the line of type with which it coöperates, but may be placed any distance therefrom and in the machine herein described, the groove is located 180° from 15 the line of type with which it coöperates, the line by which the printing is done being located at the bottom and the locking groove being located at the top of the wheel when the wheel is locked in printing position. It 20 will also be understood that these grooves are intended strictly to lock the wheel in printing position and also govern the amount of feed of paper. Instead of locating these 25 grooves on the inside of the type wheel, they may be placed on the outside thereof between the type 11, but on the opposite side of the type wheel. This modification of the type wheel and associated parts thereof is shown in Figs. 11 and 12.

30 The type wheel is locked in its various printing positions in the following manner:

Mounted to slide on the shaft 6 is the spacing arm 12. This arm has a horizontal finger 13 formed at the upper end thereof 35 and is provided with a horizontal rack 14 at the lower end thereof. It is also provided with a hub 15, formed on the arm 12 intermediate of the finger 13 and the rack 14. Through the hub 15 passes the shaft 6 and 40 the hub permits sliding engagement along the shaft. The rack 14 is engaged by the pinion 16 for the purpose of moving the spacing arm and finger into and out of engagement with the type wheel. To hold the 45 spacing finger in upright position and prevent it from tilting on the shaft 6, I provide a track 17 on the spacing arm, which slides on the hub of the feed roller 24 as the rack moves the spacing arm back and forth.

50 To justify the position of the printing wheel I provide an the left hand of it, as shown in Fig. 4, a series of annular detents 18 such as are shown in Fig. 2. Engaging with these recesses is provided the pawl 19, 55 mounted to swing on the shoulder screw 20, provided in the housing. A spring 21 is provided which holds the pawl firmly in engagement with the recesses and serves to center the type wheel in correct position so 60 that the finger 13 will make proper engagement with the recess in the type wheel.

The type wheel is positioned in place by turning the knurled wheel 8. A sight opening 21^A is provided in the casing through 65 which may be observed the series of char-

acters located on the type wheel immediately thereunder and when the character is exposed under the opening 21^A, the corresponding line will be in printing position on the bottom of the wheel.

70 Transverse to the shaft 6 is mounted the arbor 22, which arbor is fastened against rotation by the set screw 23. On this arbor is mounted to rotate the feed roller 24, the shredding wheel 25, the pinion 16 and 75 the clutch 26, through which the pinion 16 drives the shredding wheel 25. The shredding wheel 25 drives the feed roller 24 through the pin 27. On the end of the pinion 16 is provided a groove 28 in which engages the tongue 29 on the end of the clutch 26, by which the clutch 26 is positively driven from the pinion. On the hub of the clutch the shredding wheel 25 is mounted to rotate. The clutch is provided with three 80 eccentrics, 30, 31 and 32, which rotate inside of the shredding wheel. Rollers 33 are provided between the eccentrics and the shredding wheel and when the eccentrics are turned counter-clockwise as in Fig. 6 these 85 rollers connect the clutch and the shredding wheel and cause the driving of the shredding wheel. These rollers are held in an advanced position by springs.

90 A similar clutch 34 with the parts positioned in the same relation, is located at the right hand end of the feed roller in Fig. 3, for a purpose that will presently be described. The clutch 34 is provided with a hub that extends to the right through the 95 housing. On this hub a sleeve 34^A is provided, which sleeve holds the rollers of the clutch in place and supports the end of the arbor 22 and provides a ready means for assembling the arbor with the parts assembled 100 thereon. The left hand end of the arbor is supported in a lug 58 formed on the housing in which a suitable bearing is formed therefor. When the sleeve 34^A is withdrawn the arbor may be moved to the right out of engagement with the bearing, and the left hand end may be dropped down and the arbor may then be removed from the machine with all the parts attached. The plate 105 5 is removed to permit the removal of the arbor.

110 Mounted at the left hand end of the arbor 22 as shown in Fig. 3, is a bevel pinion 35, which pinion is free to turn on the arbor. The hub of this pinion is connected to the hub of the pinion 16 by means of a helical spring 36, which yieldingly transmits the movement of the pinion 35 to the pinion 16 115 in one direction. A sleeve 37 is provided which positively engages the hub of the pinion 35, the hub being provided with lugs 38 and the sleeve being provided with slots 39 for this purpose. This sleeve is cut away at the opposite end as indicated at 40 to form a shoulder which engages with the lug 41 on 120 125 130

the hub of the pinion 16, by which the pinion is driven in the reverse direction, the spring 36 driving the pinion 16 in the forward direction. The spring 36 is given an initial tension of about one turn and this normally holds the shoulder 40 against the lug 41.

Mounted in the housing, parallel to the shaft 6, is the shaft 42, which shaft is journaled in the housing at both ends. This shaft is provided with the groove 93 in which engages the screw 94 by which the shaft is held from endwise movement. The screw 94 is threaded into a lug provided in 15 the housing therefor.

On the right hand end of the shaft 42 is provided a lever 43 and a handle 44 by which the shaft may be turned. On the shaft 42 is keyed a bevel pinion 45, which 20 drives the bevel pinion 35, which in turn drives the pinion 16 to move the pointer 13. Also keyed on the shaft 42 is the cam 46, which engages with a roller 47 carried on the lever 48, which lever is mounted on the 25 pin 49. On the right hand end of this lever as shown in Fig. 3 is carried the platen 50, which is raised into engagement with the type wheel and presses the paper against it. The lever 48 is normally pressed down at 30 the right hand end by the spring 48^A. A lug 46^A is cast on the casing to limit the movement of the cam in one direction.

The shredding wheel is shown in large scale in Fig. 5 and consists of a single piece 35 of metal in which three annular grooves 51 are formed therein, separating four rings of teeth 52, which teeth are prism shape as shown in Figs. 6 and 8. Coöperating with the shredding wheel is a stripper plate 53 40 which has four slots therein in which the teeth of the shredding wheel engage or project below it. Mounted in an opening in the plate 5 is a shredding block 54, which block has four shallow grooves therein that are 45 engaged by the teeth 52. This block is adjustable up and down at one end by the set screw 55, bearing in the yoke 56. This block 54 is hinged at the other end at 57 to the plate 5.

50 As a substitute for this adjustment, I provide a shaft 63 mounted in the housing and a lug. A torsion spring 64 is provided on one end thereof. On the other end is provided a cam 65 which engages under the 55 shredding block 54 and lifts it into engagement with the shredding wheel. A screw 66 is provided to move the cam in the opposite direction and lower the block and between the spring and the screw, the position of the 60 block is fixed. On the shaft 63 is also carried the arm 67 that carries the lower feed rollers 60. A hub 68 is provided for the arm that carries the rollers and a hub 69 is provided for the hub that carries the cam 65. The hub 69 is pinned to the shaft while

the hub 68 is free to turn thereon. The hub 68 is connected to the hub 69 by the torsion spring 70 by which the rollers are yieldingly held in place. The hub 68 is slotted and a pin 71 is provided in the shaft 63 70 which engages with the arm 67 and moves the arm and lower feed roller down. By turning down the handle on the end of the shaft 63, the rollers will be drawn away from the feed roll, permitting the easy insertion of the check to any position.

75 Mounted under the plate 5 are provided the lower feed rollers 60, which rollers extend through slots in the plate 5 and coöperate with the roller 24 to feed the check. These rollers are supported by a spring plate 61, which is fastened on the under side of the plate 5 by a screw 62.

80 In Figs. 2, 3, 4 and 7 I have illustrated the inking roller and the mount therefor. This inking roller comprises a roller 75 mounted on a pin 76, carried in a yoke 77. The ends of the yoke are slotted as indicated at 78, permitting the roller to move sidewise therein, toward and away from the type 90 wheel so as to maintain a uniform or even bearing thereon. The top of the yoke is perforated to receive the two arms of the spring 79, which arms bear against the pin 76 and hold the roller yieldingly against the type 95 wheel. The recess in the handle 84 is adapted to receive and hold from endwise movement the inner or left hand end of the pin 76. This holds this pin in place in the yoke 77. When it is desired to remove the ink 100 roller from the yoke, the plate 81 carrying the handle 84 is removed from the yoke so that the pin 76 can be moved endwise therein sufficiently to allow the right hand end of the pin to disengage itself from the right 105 hand bearing in the yoke 77 as viewed in Fig. 7.

110 The end 80 of the yoke is circular in form and is fastened to the disk 81 by means of the screws 82 and 83. A handle 84 is riveted into the disk 81 as shown in Fig. 7, the disk 81 having the shape of a washer undercut on the inside so that the hub of the handle can be expanded into it. The handle is recessed to receive the end of the pin 76. The 115 disk 81 is provided with the recess 85. A screw 86 is provided, the head of which overlaps the disk 81 and holds it in position. The disk 81 can be rotated by the handle 84 until the recess 85 registers with the head of the screw 86, after which the disk is released and the roller and parts associated therewith may be removed as a unit. The washer 81 is embossed at 87 and 87^A which embossing will engage with the head of the 120 screw 86 and prevent the rotation of the disk and parts associated therewith in one direction. This is to prevent the yoke 125 from coming into contact with the type wheel. On the hood is provided a lug 90 130

on which is pivotally mounted the index or guide 91, which normally stands parallel to the shaft 6 and above the check for the purpose of guiding the placing of the check in the machine. The printed lines on the check should stand parallel to this guide. In Fig. 1 the guide is shown folded up out of the way when not in use.

The operation of my improved check writer is as follows:

The operator places the check upon the plate 5 and feeds it endwise into the machine so that it will pass between the feeding rollers and be fed lengthwise thereby to the type wheel. The feeding is accomplished by the movement of the lever 43, which lever rocks the shaft 42 and turns the bevel gear 35 and the gear 16 through the spring 36, causing the rack 14 to be driven forward, carrying with it the finger 13 into locking engagement with the printing wheel. When this finger meets the end of its movement, the spring yields to permit the handle 43 to go to the end of its movement. The last part of the movement of the handle 43 causes the raising of the platen 50 which does the printing. On the reverse movement of the handle 43, after the platen has moved away from the printing wheel, the clutch 26, driven by the sleeve 37, acts to drive the shredding wheel and the feed roller 24, which act together to feed the paper and shred it on the line where the printing will take place in the next printing operation. The lever can be moved partially forward and back sufficiently to feed and shred the paper without moving the platen so that the paper can be properly positioned and shredded before the printing begins. The shape of the cam 46 delays the lifting of the platen sufficiently to secure this result. When the lever 43 has reached its starting point, the finger 13 has been withdrawn from the type wheel and the type wheel has been released to unlock for rotation to a new position for the printing of another impression after which the printing operation may be repeated as above described. By reason of the clutch 26 the shredding wheel and the feed roller operate only on the reverse movement of the lever and are prevented from moving in the other direction on the forward movement of the lever by reason of the clutch 34.

I claim:

1. In a check writing machine, a type cylinder having a series of lines of type on the outside thereof, said lines being arranged parallel to the axis thereof, a series of parallel grooves on the outside of the cylinder, each of said grooves having a length complementary to the length of one of the lines of type, a series of characters corresponding with the lines of type, and a series of dents 65 corresponding with the lines of type.

2. In a check writing machine, a type cylinder having a series of lines of type on the outside thereof, said lines being arranged parallel to the axis thereof, a series of parallel grooves on the inside of the cylinder, 70 each of said grooves having a length complementary to the length of one of the lines of type, a series of characters corresponding with the lines of type, a series of positioning detents corresponding with the lines of type, 75 a spacing arm having a finger thereon adapted to engage with said grooves.

3. In a check writing machine a type cylinder having a series of lines of type on the outside thereof, said lines being arranged 80 parallel to the axis thereof, a series of parallel grooves on the inside of the cylinder, each of said grooves having a length complementary to the length of one of the lines of type, a series of characters corresponding 85 with the lines of type, a series of positioning detents corresponding with the lines of type, a spacing arm having a finger thereon adapted to engage with said grooves, said spacing arm having a rack thereon, a pinion engaging 90 with said rack for driving said arm, means for driving said pinion and rack variable distances.

4. In a check writing machine a stationary arbor, two pinions mounted to rotate thereon, 95 a helical spring connecting said pinions by which one drives the other, said driven pinion operating to move a spacing finger by engagement with a rack thereon.

5. In a check writing machine, a stationary arbor, two pinions mounted to rotate thereon, a helical spring connecting said pinions by which one drives the other, a sleeve fastened to one of said pinions and having a loose engagement with the other 100 pinion, said sleeve driving the second pinion supplemental to the spring, said driven pinion operating to move a spacing finger by engagement with a rack thereon.

6. In a check writing machine, a stationary arbor, a pinion mounted to turn thereon, 110 a clutch member mounted to turn on the arbor, means for driving said clutch member from said pinion, a shredding wheel mounted to turn on the clutch member, rollers interposed between the clutch member and the shredding wheel by which the shredding wheel is driven from the clutch member.

7. In a check writing machine, a stationary arbor, a pinion mounted to turn thereon, 115 a clutch member mounted to turn on the arbor, means for driving said clutch member from said pinion, a shredding wheel mounted to turn on the clutch member, rollers interposed between the clutch member and the shredding wheel by which the shredding wheel is driven from the clutch member, a feed roller mounted to turn on said arbor, means for driving said rollers from the shredding wheel at one end. 130

8. In a check writing machine, a stationary arbor, a pinion mounted to turn thereon, a clutch member mounted to turn on the arbor, means for driving said clutch member from said pinion, a shredding wheel mounted to turn on the clutch member, rollers interposed between the clutch member and the shredding wheel by which the shredding wheel is driven from the clutch member, a feed roller mounted to turn on said arbor, means for driving said roller from the shredding wheel at one end, a clutch at the other end of the feed roller adapted to prevent the backward rotation of the feed roller. 10
- 15 9. In a check writing machine, the combination of an arbor, a pinion, a helical spring and sleeve, a pinion, a clutch, a shredding wheel, a feed roller and a clutch mounted thereon in the order named, said parts being assembled outside of the machine, bearings in the machine for each end of the arbor in which the arbor can be mounted with the parts in place thereon. 20
- 25 10. In a check writing machine, a shredding wheel having a series of rings of prism shaped teeth thereon, each of said teeth being capable of cutting an I-shaped slit in the paper. 11. In a check writing machine, a shredding wheel having a series of rings of prism shaped teeth thereon, each of said teeth being capable of cutting an I-shaped slit in the paper, a shredding block having a series of grooves therein, one for each ring of teeth 30
- 35 on the wheel, said teeth making a close fit with the groove with which it engages. 12. In a check writing machine, the combination of a shredding wheel having a series of rings of prism shaped teeth thereon, each of said teeth being capable of cutting an I shaped slit in the paper, a shredding block having a series of grooves therein, one for each ring of teeth on the wheel making a close fit between the teeth and the groove so as to shear and cut the paper, said block having means of adjustment up or down. 40
- 45 13. In a check writing machine, the combination of a casing, a shaft mounted therein, a type wheel rigidly fastened to said shaft, a spacing arm mounted to slide on the shaft, said shaft extending outside of the casing and having an annular circumferential groove therein, a screw in said casing having a large head adapted to engage in said groove and fix the position of the shaft in the casing. 50
- 55 14. In a check writing machine, the combination of a casing, a shaft mounted therein, a type wheel rigidly fastened to said shaft, a spacing arm mounted to slide on the shaft, said shaft extending outside of the casing and having an annular circumferential groove therein, a screw in said casing having a large head adapted to engage in said groove and fix the position of the shaft 60
- 65 in the casing, the inner end of said screw engaging with said spacing arm and limiting its movement in one direction. 15. In a check writing machine, the combination of a casing having a base in front and at the sides and shoulders at the rear, a table adapted to rest on said base at the front and sides and engage under said shoulders at the rear. 70
- 75 16. In a check writer the combination of a casing, a crank shaft mounted to rock therein, a cam on and rigidly fastened to said shaft, a lever mounted to rock in said casing, a roller on one end thereof with which said cam engages to depress that end of the lever and raise the other end of the lever, a platen on the other end of the lever, said platen and lever being made in one piece. 80
- 85 17. In a check writer, the combination of a casing, an ink roller mounted therein, a yoke supporting said roller, said yoke having one end circular, a washer to which said end is fastened, a handle fastened in said washer. 90
- 95 18. In a check writer, the combination of a casing, an ink roller mounted therein, a yoke supporting said roller, said yoke having one end circular, a washer to which said end is fastened, a handle fastened in said washer, a circular opening in the casing into which the roller can be introduced, said washer bearing against the outside of the casing and said circular end fitting in the circular opening of the casing. 100
- 105 19. In a check writer, the combination of a casing, an ink roller mounted therein, a yoke supporting said roller, said yoke having one end circular, a washer to which said end is fastened, a handle fastened in said washer, a circular opening in the casing into which the roller can be introduced, said washer bearing against the outside of the casing and said circular end fitting in the circular opening of the casing, a screw having a large head overlapping said washer to hold it in place in the casing, a recess in said washer which permits the washer to pass the head of said screw, permitting the removal of the roller from the machine. 110
- 115 20. In a check writer, the combination of a casing, an ink roller mounted therein, a yoke supporting said roller, said yoke having one end circular, a washer to which said end is fastened, a handle fastened in said washer, a circular opening in the casing into which the roller can be introduced, said washer bearing against the outside of the casing and said circular end fitting in the circular opening of the casing, a screw having a large head overlapping said washer to hold it in place in the casing, a recess in said washer which permits the washer to pass the head of said screw permitting the removal of the roller from the machine, said 120
- 125 130

yoke, washer and handle being turned to bring the recess into register with the screw when the roller is introduced into or withdrawn from the casing, an embossing on the 5 washer to prevent it from being turned in the wrong direction.

21. In a check writer, the combination of a casing, an ink roller mounted therein, a yoke supporting said roller, said yoke having one end circular, a washer to which said 10 end is fastened, a handle fastened in said washer, a roller and shaft supported in said yoke, the inner end of said handle being hollow to receive and hold in place the long 15 end of said shaft.

22. In a check writer, the combination of a casing, an ink roller mounted therein, a yoke supporting said roller, said yoke having one end circular, a washer to which said 20 end is fastened, a handle fastened in said washer, a roller and shaft supported in said yoke, the inner end of said handle being hollow to receive and hold in place the long 25 end of said shaft, the opposite end of said shaft having a short engagement with the yoke, permitting the said end to be disengaged from the yoke on the removal of the handle.

23. In a check writer, an upper feed roll 30 and a shredding wheel, a lower feed roll and a shredding block, means for moving the lower feed roll and shredding block away from the upper feed roll and shredding wheel to permit the introduction of a check.

35 24. In a check writer, an upper feed roll and a shredding wheel, a lower feed roll and a shredding block, means for moving the lower feed roll and shredding block away from the upper feed roll and shredding 40 wheel to permit the introduction of a check, means for returning the lower feed roll and shredding block to operative position.

25. In a check writer, an upper feed roll and a shredding wheel, a lower feed roll and 45 a shredding block, a rock shaft for moving

the lower feed roll and shredding block away from the upper feed roll and shredding wheel to permit the introduction of a check.

26. In a check writer, an upper feed roll 50 and a shredding wheel, a lower feed roll and a shredding block, a rock shaft for moving the lower feed roll and shredding block away from the upper feed roll and shredding wheel to permit the introduction of a 55 check, a spring on said rock shaft to turn it and return the lower feed roll and shredding block to operative position.

27. In a check writer, an upper feed roll 60 and a shredding wheel, a lower feed roll and a shredding block, a rock shaft for moving the lower feed roll and shredding block away from the upper feed roll and shredding wheel to permit the introduction of a 65 check, a spring on said rock shaft to turn it and return the lower feed roll and shredding block to operative position, an adjustable stop on the casing adapted to limit the return movement of said parts and fix the position thereof.

28. In a check writer a casing and a table, a sight gage pivotally mounted on the casing above the table and normally extending outwardly and adapted to be folded up 70 against the casing.

29. In a check writer the combination of a casing, a crank shaft mounted to rock therein, a cam on and rigidly fastened to said shaft, a lever mounted to rock in said casing, said lever being engaged and moved 80 by the cam when the crank shaft is moved in one direction and permitting said lever to return to normal position when said cam is moved in the opposite direction, and a stop lug on the casing to engage the cam 85 and limit its movement in said opposite direction.

In testimony whereof I affix my signature.

ALBERT M. WARD.
